UNITED STATES PATENT OFFICE

DANIEL B. DANIELSON, OF MILWAUKEE, WISCONSIN

VENEER BOND

Application filed August 23, 1928. Serial No. 301,450.

This invention relates to improvements in veneer bond, for use in building construction.

It is the primary object of the present invention to provide in building constructions, 5 a means for forming an efficient bond between veneer walls of brick, stone, or terra cotta, and the inner walls.

A further object of the invention is to provide a veneer bond in which the veneer engaging portions are quickly attachable as the veneer-wall progresses and are adjustable for 10 irregular spacing and are adapted to be embedded and concealed in the mortar joints of the veneering medium.

15 A further object of the invention is to provide a veneer bond which may be installed very easily and quickly and which materially reduces construction costs.

20 A further object of the invention is to provide a veneer bond which is of very simple construction, is inexpensive to manufacture, is strong and durable, and is well adapted for the purpose described.

With the above and other objects in view, 25 the invention consists of the improved veneer board, and its parts and combinations as set forth in the claims, and all equivalents thereof.

In the accompanying drawing in which 30 the same reference characters indicate the same parts in all of the views:

Fig. 1 is a horizontal sectional view through a portion of a concrete inner wall with the form boards in place and several 35 of the improved veneer bonds embedded in said inner wall;

Fig. 2 is a fragmentary front view of a concrete inner wall after the removal of the form boards showing a veneer bond cast in 40 the wall;

Fig. 3 is a vertical sectional view of a wall constructed in accordance with the invention showing the veneer bond forming an anchoring means between an inner concrete wall and an outer brick veneer wall;

Fig. 4 is a sectional view taken on line 4—4 of Fig. 3; and

Fig. 5 is a fragmentary detail view of the 50 rear construction of a veneer engaging mem-

ber showing its engagement with a vertical rod portion of the device.

Referring now more particularly to the drawing, it will appear that the numeral 8 indicates a cast concrete wall in which the 55 concrete is poured between inner and outer form boards 9 and 10 respectively. In the construction of concrete walls in which the improved veneer bond is used, the inner faces of the outer form boards 10 have secured thereto vertically extending spaced-apart 60 soffit members 11 provided with vertical grooves 12.

Each inner wall engaging member of the 65 veneer bond consists of an elongated rod 13 having spaced-apart looped or off-set portions 14. When the wall is poured each rod member is disposed so that its off-set looped portions 14 are firmly embedded in the concrete while the rod portions are received by 70 the vertical grooves 12 of the soffit members 11. The result is that after the wall has set and the form boards and attached soffit members are removed, the outer surface of the 75 wall will be formed with vertical grooves 15, shown in Fig. 2, in which the vertical rod portions 13 are accessibly disposed.

The outer veneer wall is built up in the usual manner against the outer surface of the inner wall 8, said veneer wall being 80 formed of units 16 of brick, stone, terra cotta, or other suitable material joined by interposed layers of mortar 17. At intervals, as the veneer wall progresses vertically it is necessary to form a bond or anchor between 85 said veneer wall and the inner wall. For that purpose split rings 18 are provided, said rings being formed of yieldable metal and having overlapping looped free end portions 19. When it is desired to attach one of said 90 rings, the same is held in a plane with a vertical rod portion 13 and pushed into engagement with the rod, with the same passing between the ends 19, and then the ring is turned horizontally and the engagement is as shown 95 in Figs. 4 and 5. The ring is then disposed flat on the upper face of one of the units 16 and is embedded in the mortar layer 17 between said unit and the one next placed thereabove.

It will thus be seen that with the improved veneer bond an effective and quickly arranged bonding or anchoring medium is effected between the inner wall and the veneer wall in building constructions. The off-set portions of the inner wall engaging members are embedded and cast in the inner wall and the rod portions thereof are accessible for the quick attachment of the bonding rings 18 at whatever points desired. The bonding rings are anchored in the veneer wall and are concealed and are also firmly attached to the rod portions 13. Furthermore, the improved veneer bond is of simple and novel construction, and is well adapted for the purposes described.

What I claim as my invention is:

1. In a building construction, an inner wall having a vertical groove in its outer face, an elongated vertical, non-flexible rod formed with integral off-set portions, the off-set portions being secured to said inner wall, and the entire vertical rod portion being disposed within said groove and spaced slightly from surfaces of the wall defining said groove, an outer veneer wall, and a bonding member anchored between adjacent units of the veneer wall and attached to said vertical rod.
2. In a building construction, an inner wall having a vertical groove in its outer face, an elongated vertical, non-flexible rod formed with integral off-set portions, the off-set portions being secured to said inner wall, and the entire vertical rod portion being disposed within said groove and spaced slightly from the surfaces of the wall defining said groove, an outer veneer wall, mortar layers between adjacent horizontal faces of units of the veneer wall, and a plurality of vertically spaced bonding members embedded in said mortar layers and attached to spaced portions of said vertical rod.
3. In a building construction, an inner wall having a vertical groove in its outer face, an elongated vertical rod formed with off-set portions, the off-set portions being disposed within said groove and secured to said inner wall, and the entire vertical rod portion being spaced slightly throughout its length from surfaces of the wall defining the groove, an outer veneer wall, and a bonding member anchored between adjacent units of the veneer wall and quickly attachably and vertically adjustably engaging said vertical rod within the groove.
4. In a building construction, an inner cast wall having a vertical groove in its outer face, an elongated vertical rod formed with integral off-set portions, the off-set portions being embedded in said inner wall, and the vertical rod portion being disposed within said groove and spaced throughout its length from the surfaces of the wall defining groove, an outer veneer wall, mortar layers between

adjacent horizontal faces of units of the veneer wall, and a plurality of split ring anchoring members embedded horizontally in vertically spaced mortar layers and attached to said vertical rod.

In testimony whereof, I affix my signature.

DANIEL B. DANIELSON.
